LOCOMOTIVE STOKER

Charles J. Surdy, Tuckahoe, N. Y., assignor to
The Standard Stoker Company, Incorporated,
a corporation of Delaware

Application May 5, 1937, Serial No. 140,828

9 Claims. (Cl. 110—104)

This invention relates to locomotive stokers and particularly to locomotive stokers of the type shown and described in Patent No. 1,829,044, granted October 27, 1931, to M. C. M. Hatch.

Stokers of the patented type are proposed for installation on locomotives wherein the foundation or mud ring of the locomotive firebox is spaced so closely above the locomotive frame that it is not feasible to pass a stoker conduit between the frame and mud ring and thence upwardly into the firebox. Accordingly, the stoker conduit enters the firebox immediately above the mud ring through an opening which extends above the locomotive cab deck and is substantially of inverted U-shape.

It is the principal object of this invention to provide, in a stoker adapted to enter the firebox through an opening above the foundation ring, a novel protective grate which surrounds that portion of the stoker conduit within the furnace or firebox.

More specifically, it is an object of this invention to provide a novel protective grate for that portion of the stoker conduit within the firebox, such protective grate being supported upon the central grate bearer bar of the furnace or firebox.

A further object of this invention resides in so constructing the protective grate that it rests upon the central bearer bar of the furnace and also serves as a support for fire grates of the furnace.

A still further object of this invention resides in constructing the lower portion of the protective grate as an integral casting arranged to be seated upon the customary central grate bearer bar of the firebox and also formed to support the upper portion of the protective grate, which latter portion may include several sections.

These and other objects and advantages of the present invention will become apparent upon reading of the following description in connection with the accompanying drawings, in which

Fig. 1 is a vertical section through the central portion of the rearward end of a locomotive showing the stoker in side elevation and the novel protective grate structure partly in similar section and partly in side elevation;

Fig. 2 is a view in plan taken on the line 2—2 of Fig. 1 with portions of the locomotive cab deck removed;

Fig. 3 is a sectional view taken on the line 3—3 of Fig. 4; and

Fig. 4 is a sectional view from within the firebox taken on the line 4—4 of Fig. 1 with the stoker conduits in front elevation.

In these drawings, L indicates a locomotive having a boiler 10 supported above the frame 11. The boiler 10 comprises a firebox 12 having a backwall 13 and a cab deck 14 extending rearwardly therefrom. A foundation or mud ring 15 forms the base of the firebox 12 and to which the inner and outer sheets 16 and 17, respectively, of the firebox are secured. Extending longitudinally and centrally of the firebox is a bar 18, the upper surface 19 of which is disposed slightly 10 above the lower portion of the foundation ring 15. The bar 18 is provided with recesses such as 20 in each of which is received a trunnion 21 formed on the inner side of grate bars 22. A similar arrangement supports the outward ends 15 of the grate bars adjacent the sides of the firebox. Attached in any known manner to the inner side of the foundation ring 15 is a casting 23 which forms a support for the rearward end of the bar 18 and to which are also secured the ash 20 pan sheets 24.

The foundation ring 15 is provided with an upstanding portion 25 of inverted U-shape arranged to form an aperture 26 in the firebox backwall 13. This aperture 26 extends upwardly 25 from the foundation ring 15 to a point above the cab deck 14 and is divided by a plate element 27 into an upper opening 28 and a lower opening 29. A firedoor 30, which may be operated manually or by power means, closes the upper opening 30 28. Access to the interior of the firebox is gained through the opening 28.

Normal firing of the firebox is accomplished by means of a stoker S comprising a tubular conduit 31 having an upturned elbow 32 at its forward end. The elbow 32 is secured to the tubular conduit 31 by bolts such as 33 and forms, in effect, an upwardly and forwardly extending continuation of the tubular conduit which conduit is secured to the foundation ring by support brackets 34, 35. At its rearward end, the tubular conduit 31 is universally connected at 36 to a conduit 37 leading forwardly from the tender fuel bin (not shown). The means for urging fuel along the conduits 31, 37 and thence upwardly through the elbow 32 is in the form of a conveyor screw 38, the forward end of which terminates adjacent the forward end of the tubular conduit 31.

The elbow 32 has an upwardly directed fuel discharge mouth 39 which lies wholly within the firebox 12 and at a level below the plate element 27. That portion of the lower opening 29 which is above the cab deck 14 is closed against outside exposure by a shield 9 which is secured to the 50 40 45 55 60 65 70 75 80 85 90 95 100 105 110 115 120 125 plate element 27 at its upper end and partially embraces the stoker tubular conduit 31. Immediately beneath the forward end portion of the plate element 27, the elbow 32 has secured thereto by bolts 40 a distributor member 41. Fluid under pressure is conducted to the distributor member 41 by supply lines 42 and thence is discharged through jet apertures 43 in a plane above and parallel to the upper terminal portion 44 of the discharge mouth 39. As the fuel is urged upwardly through the elbow 32 by the conveyor screw 38, it rises above the terminal portion 44 and into the zone of action of the distributor member 41. The blast of pressure fluid issuing from the jet apertures 43 of the member 41 propels the fuel forwardly and laterally over the firebed. To give proper support for the fuel as it is propelled forwardly by the distributor member 41, a table 45 embraces the terminal portion 44 of the elbow 32 and is seated upon a ledge 8 formed therewith.

Since the elbow 32 extends into the firebox a substantial distance, a protective grate G is utilized to protect it from the heat of the firebox. Heretofore, it has been customary to support the protective grate from the center grate bearer bar which was of special construction. In some instances, it has been proposed to suspend the protective grate from the stoker discharge conduit, but this imposes a considerable strain on the conduit if a protective grate of the substantial size necessary is used.

In the present invention, the protective grate G is supported on the bar 18 which bar is of usual construction. The protective grate G comprises a lower section 46 which in horizontal section is substantially U-shaped with the outer ends 47 thereof extending closely adjacent the inner sheet 16 of the firebox. Extending longitudinally at the lower central portion of the U-shaped section 46 is an inverted channel 48 which is integrally formed with the section 46 and otherwise firmly related therewith by ribs such as 49. The inverted channel 48 is adapted to fit over the bar 18 and is secured thereto by bolts 50. Each of the outer ends 47 is secured by bolts 51 to lugs 23a formed with the ash pan support casting 23. In this manner, the lower section 46 of the protective grate G is firmly secured to the conventional grate bearer bar 18.

Atop the lower section 46, is a grate element 51 which may be in the form of side sections 52, 53 removably carried by the lower section below the table 45. Air entering through the ash pan is entrained through slots 54 formed in the grate sections 46, 52, and 53 for cooling the same. Each lateral side of the U-shaped lower section 46 is provided with recesses such as 55, each arranged to receive a trunnion 56 of a grate bar 57. These grate bars 57 are shorter than the main grate bars 22 and at their outermost ends are supported in the usual manner along the inner side sheets of the firebox.

From the foregoing, those familiar with the art will readily understand that by the present invention a novel stoker protective grate structure has been devised which requires no changes in the center grate bearer bar while affording adequate support for the grates at each side of the stoker protective grate.

I claim:

1. In a firebox having an upstanding wall provided with an opening therein, the combination of grate bearer bar in the lower portion of said firebox, a stoker conduit passing through said

opening into said firebox, said grate bearer bar extending longitudinally of the firebox and being substantially straight throughout, a portion of said grate bearer bar extending under that portion of the conduit within the firebox, a protective grate embracing such portion of the conduit, said protective grate being supported by said grate bearer bar, a firebox grate at each side of said protective grate and means formed with the lower end of said protective grate forming a support for said firebox grates.

2. In a firebox having an upstanding wall provided with an opening therein, the combination of a grate bearer bar in the lower portion of said firebox, a stoker conduit passing through said opening into said firebox, said grate bearer bar extending longitudinally of the firebox and being substantially straight throughout, a portion of said grate bearer bar extending under that portion of the conduit within the firebox, a protective grate embracing such portion of the conduit, said protective grate being secured to said grate bearer bar, a firebox grate at each side of said protective grate and means formed with the lower end of said protective grate forming a support for said firebox grates.

3. In a firebox having an upstanding wall provided with a base member and an opening extending above said base member, the combination of a great bearer bar in the lower portion of said firebox and a support for said grate bearer bar, a stoker conduit passing above said base member through said opening into said firebox, said grate bearer bar extending longitudinally of the firebox and being substantially straight throughout, a portion of said grate bearer bar extending under that portion of the conduit within the firebox, a protective grate embracing such portion of the conduit, said protective grate being supported by said grate bearer bar, and means at each side of said grate bearer bar forming an additional support for said protective grate.

4. In a firebox having an upstanding wall provided with a base member and an opening extending above said base member, the combination of a grate bearer bar in the lower portion of said firebox and a support for said grate bearer bar, a stoker conduit passing above said base member through said opening into said firebox, said grate bearer bar extending longitudinally of the firebox and being substantially straight throughout, a portion of said grate bearer bar extending under that portion of the conduit within the firebox, a protective grate embracing such portion of the conduit, said protective grate being supported by said grate bearer bar, means at each side of said grate bearer bar forming an additional support for said protective grate, and a firebox grate at each side of said protective grate supported thereby.

5. As an article of manufacture, a stoker conduit protective grate comprising a U-shaped section, and a channel portion formed integrally with said U-shaped section, said channel portion opening downwardly when said protective grate is in operative position, said channel portion extending approximately parallel to the sides of said U-shaped section and being spaced equidistant therefrom.

6. As an article of manufacture, a stoker conduit protective grate comprising a U-shaped section, a channel portion formed integrally with said U-shaped section, said channel portion opening downwardly when said protective grate is in operative position, said channel portion extending

approximately parallel to the sides of said U-shaped section and being spaced equidistant therefrom, and firebox grate supporting means formed along the sides of said U-shaped section.

- 5 7. In a firebox having an upstanding wall provided with an opening therein, the combination of a grate bearer bar in the lower portion of said firebox, a stoker conduit passing through said opening into said firebox, said grate bearer bar being substantially straight throughout and extending under that portion of the conduit within the firebox, and a protective grate embracing such portion of the conduit, said grate comprising a 10 U-shaped section and means between and rigid with the sides of said U-shaped section engaging the portion of said grate bearer bar under said conduit for supporting said protective grate on said grate bearer bar.
- 15 8. In a firebox having an upstanding wall provided with an opening therein, the combination of a grate bearer bar in the lower portion of said firebox, a stoker conduit passing through said opening into said firebox, said grate bearer bar

extending under that portion of the conduit within the firebox, and a protective grate embracing such portion of the conduit, said grate comprising a U-shaped section and a downwardly opening channel portion between the sides of said U-shaped section, the portion of said grate bearer bar under said conduit being received in said channel portion and forming a support for said protective grate.

9. In a firebox having an upstanding wall provided with an opening therein, the combination of a grate bearer bar in the lower portion of said firebox, a stoker conduit passing through said opening into said firebox, said grate bearer bar extending longitudinally of the firebox and being 15 substantially straight throughout, a portion of said grate bearer bar extending under that portion of the conduit within the firebox, a protective grate embracing such portion of the conduit, said protective grate being supported by said grate bearer bar, and means at each side of said grate bearer bar forming additional support means for said protective grate.

CHARLES J. SURDY.
